METHOD OF AND APPARATUS FOR TAMPING
WASTE IN FILTER CARTRIDGESHilmer Dahl, Chicago, Ill., assignor to Wm. W.
Nugent & Co., Inc., Chicago, Ill., a corporation
of Illinois

Application July 14, 1947, Serial No. 760,823

4 Claims. (Cl. 226—19)

1

This invention relates to methods and apparatus for packing waste or similar filtering material in filter cartridges of the kind having a continuous fabric cover or envelope and more particularly, to filter cartridges, of the kind described, also having a perforated metallic core.

Among the objects of the invention is to provide an improved method for packing the filtering material within a continuous length of tubular fabric to form a filter cartridge of the character hereinabove mentioned.

A further object is to provide an improved apparatus for forming a filter cartridge of the character hereinabove mentioned.

Other objects and advantages of the invention will appear from time to time as the following description proceeds.

The invention may best be understood by reference to the accompanying drawings in which:

Figure 1 is a perspective view of a completed cartridge of the kind to which my invention relates.

Figure 2 is an enlarged vertical section of the cartridge shown in Figure 1.

Figure 3 is a perspective view of a filling form constituting part of the filling apparatus used in connection with my improved filling process.

Figure 4 is a vertical section taken through the filling form shown in Figure 3, illustrating one of the first steps in applying a continuous length of fabric tube or "stockinet" to the filling form preparatory to the packing operation.

Figures 5 and 6 respectively, show subsequent steps in the process including affixing the "stockinet" temporarily to the filling form preparatory to the packing operation.

Figure 7 is a view similar to 5 and 6, but showing the packing or filling process in successive steps.

Figure 8 is a view similar to the preceding figures, but showing the cartridge after it has been completely packed with filtering material, and illustrating the method of lapping one end of the "stockinet" over the proximate end of the cartridge.

Figure 9 is a sectional view of the cartridge after it has been removed from the filling form, but with a temporary core member retained therein, and illustrating the method of preparing the apparatus for lapping and tucking the opposite end of the "stockinet" into the complete assembly.

Figure 10 is a side view of the permanent core member of the kind adapted for final assembly in the completed cartridge.

2

Figure 11 is a section taken on line 11, 11 of Figure 10, but drawn to a larger scale than the latter figure.

Figure 12 is a perspective view of a clamping fixture forming part of the apparatus for inserting the permanent core in the filter cartridge.

Figure 13 is a longitudinal section showing the clamping fixture illustrated in Figure 12, together with associated parts of the apparatus for inserting the permanent core in the filter cartridge.

Referring now to details of the embodiment of my invention illustrated in the drawings, the form and construction of a typical filter cartridge to

15 which the present invention is directed is indicated at 10 in Figures 1 and 2. Such a typical filter cartridge consists essentially of a central core 11, preferably formed of metal in generally tubular shape, open at both ends and having perforated corrugated side walls 12, with a plurality of perforations 13 therethrough. Said core is surrounded by a cylindrical filtering member, including a fabric cover or sheath 14, filled with filtering material 15 such as waste.

20 Figure 2 is a perspective view of a clamping fixture forming part of the apparatus for inserting the permanent core in the filter cartridge.

25 The fabric cover 14 is preferably formed of a continuous length of tubular knitted material commonly termed a "stockinet," which tubular material is somewhat elastic, capable of being formed in a continuous envelope completely surrounding the cylindrical, hollow body of filtering material 15. One of the principal objects of the present invention is to provide a simple and economical method and apparatus for packing the filtering material within the fabric cover or envelope 14 in assembled position around the central core 11 in such a manner as to overlap the free ends of the stockinet or tubing fabric with each other to form a filter cartridge which will maintain its shape while being packed or transported for assembly or replacement in a filter casing.

30 It will be understood that the filter cartridge shown in Figures 1 and 2 is only illustrative of the wide variety of forms, shapes and sizes of filter cartridges which may be employed for filtering oil or other liquids when used in filter casings of various kinds well known in the art.

35 Referring more particularly to the method and apparatus for forming the typical filter cartridge shown in Figures 1 and 2, a filling form 20 in Figures 3 and 4 is employed which is normally closed at its bottom end 21 and is provided with a removable clamping ring 22 surrounding its open upper end 23. The clamping ring may be 40 of any suitable form, herein consisting of a split

metallic band connected at adjacent ends by a bolt 24 hinged to one end of said band and swingable between spaced lugs 26, 26 fixed on the other end of said band and adjustable with respect to said lugs by a nut 27.

The side walls of the filling form 20 are preferably split longitudinally at 31, 31 from adjacent the bottom end 21, so that side wall portions 32, 32 of said form may be readily expanded to facilitate the removal of the cartridge from the filling form, as will hereinafter more fully appear.

As shown in Figure 4, the filling form 20 is provided with a temporary central tubular core member 35 which is removably mounted therein, as on an upright stud 36 formed integrally with the bottom wall 21 and terminating slightly below the open upper end of said form. The removable core member 35 normally extends slightly above the rim of the filling form and is 20 hollow throughout its length, excepting for a restricted annular shoulder 37 formed close to its upper end.

In initially preparing the filling form for packing, an annular ring 39 having a grooved under-surface 40 is fitted around the upper lip of the form 20. A stockinet indicated at 30 is cut to the length required for forming the final cover or envelope of the cartridge. One end 30^a of the stockinet is inserted in the upper end of the removable core 35, with a substantial part of its terminal portion projected through the restricted shoulder portion 37 within said tube, as shown in Figure 4. The main body portion of the stockinet may be drawn loosely over the outer side of the form 20, as shown in this latter figure. A cap member 41 is attached to the upper end of the tube 35 to secure the upper or first named end of said stockinet to said tube. In the form shown, the cap 41 has an integral, depending stud 42, screw-threaded at its lower end for engagement in a threaded aperture 43 in the upper end of the upright stud 36, as shown in Figure 5.

The intermediate portion of said tube or stockinet is then positioned within the filling form. To insure the smooth and even disposition of the stockinet along the sides of the form 20, a funnel-like tubular member indicated at 45 is inserted in close-fitting telescopic engagement within said form, as shown in Figure 5, so as to stretch the outer portion of the stockinet along the inner surface of the form 20.

The opposite end portion 30^b of the stockinet which, to distinguish from the first named end will be termed herein, the "second" end, is then secured to the outer rim of the filling form by means of the clamping ring 22, as shown in Figure 5. A sufficient length of fabric tubing is left below the clamping ring to provide an overlap for the upper end of the cartridge, as will hereinafter be described.

A smaller tubular member 46 may then be fitted telescopically over the cap 41 and core 35 to the full depth of the form, so as to dispose the inner portion of the stockinet in proper relation along core member 35, as shown in Figure 6. If desired, a suitable rod or stick 47 may also be inserted in the filling form to insure proper positioning of the stockinet against the bottom of said form, as indicated in dotted lines in Figure 6.

The smaller tube 46 and stick 47 are then removed from the form, and filtering material may then be packed in the filling form by introducing

it in relatively small quantities through the flared upper end of the funnel-like member 45, and tamping it down while the stockinet is supported against the inner walls of said form. The funnel-like member 45 is gradually raised as the filling proceeds, as indicated in Figure 6, or in some cases, it may be found practicable to remove the funnel-like member 45 entirely from the form, once the filling operation has commenced.

Figure 7 illustrates a further stage in the filling process in which a hollow plunger 49 may be employed to apply pressure to successive layers of filtering material as they are inserted in the form. Figure 7 also shows a part-length, funnel-like member 50, which is shorter than the first named funnel member 45, and may be substituted for the latter if desired, after the form becomes partially filled. In either case, the funnel members 45 or 50 are gradually elevated as the packing operation proceeds, so that the filtering material will fill the entire space between the inner and outer upright portions of the stockinet in supporting engagement with the side wall 32 and the removable core member 35.

When the form is completely filled with filtering material to a level with the upper rim of the filling form, the cap 41 is unscrewed from the fixed central stud 36 and is removed from the top of the core member 35. This releases the first end of the stockinet, which was previously secured by the cap member 41. The said first end of the stockinet is then drawn outwardly to lap over the exposed upper surface of the filling material, and its extreme outer end is then tucked downwardly around the outer edge of the filling material. Figure 8 illustrates a preferred method of accomplishing this tucking operation, with the aid of a relatively short cylindrical member 55 made of thin metal adapted to fit closely within the rim 39 at the upper end of the filling form. The first end portion of the stockinet is drawn outwardly over the outer edge of the rim, as indicated in dotted lines in Figure 8: the tubular member 55 is then applied to the form and pressed downwardly with a twisting movement so as to tuck the free end of the stockinet inside of the form but outside of the adjacent filling material as indicated in Figure 8. When the tubular member 55 is withdrawn from the form the first end of the stockinet will be retained in its fully tucked underlapped position, by the expanding pressure of the filling material, as indicated in Figure 9.

55 The cartridge with its filling material is then removed from the filling form 20, but with the removable core 35 retained therein, as indicated in Figure 9.

To remove the cartridge from the filling form 60 20 the clamping ring 22 is released and removed so as to free the second end portion of the stockinet. This will permit access to the ring 38 and permit it to be removed from the upper edge of the filling form. Thereafter, the side wall 65 portions 32, 32 may be spread outwardly to permit the cartridge to be readily removed from the filling form in the condition shown in Figure 9.

The second end portion of the stockinet 30 is then lapped over the first end portion of the stockinet at the upper end of the cartridge, with its extreme end permanently tucked into the opening in the upper end of the cartridge and retained by the permanent core member 41. To accomplish this, the extreme end of said second 75 portion is tucked into the upper end of the re-

movable core member 35 as shown in Figure 9, and the lower end of the permanent core member 11 is then inserted in the upper end of said removable core member so as to retain the extreme end of the stockinet in frictional engagement between the bottom of the permanent core member 11 and the shoulder 37 in the removable core member 35.

To carry out this part of the process, I mount the cartridge in a suitable holding device 60, shown in detail in Figures 12 and 13. Said holding device consists of two hinged jaws 61 and 62, which are open at their opposite ends and are connected together by detachable fastenings 63, 63 which may be similar in construction to the detachable fastenings 24, 25, 26 heretofore described for securing the ends of the split clamping ring 22 together. The holding device 60 is mounted on a suitable base 64, which in turn is mounted on an elongated support 65, which for the purpose of illustration in Figure 13 is disposed in a horizontal plane.

The cartridge indicated at 10°, together with the temporary core member 35 positioned therein as shown in Figure 9, is first mounted in the clamping device 60. The permanent core member 11 is then forced against the upper end of the temporary core member 35 by suitable means, such as a plunger 66 which engages the opposite end of the core member 11, to force the temporary core member 35 out of the cartridge and replace it by the permanent core member 11. A stop member 67 may be mounted on the support 65 at a predetermined distance from the clamping member 60 so that the endwise movement of the temporary core member 35 will be stopped when the permanent core member 11 reaches its desired final position in the cartridge.

It will be observed that since the second end of the stockinet is initially retained between the bottom end of the permanent core member and the shoulder 37 of the temporary core member during this ejecting movement, the free end of the stockinet will be pushed inwardly with the two core members so as to be drawn tightly over the adjacent end of the cartridge and thence inwardly into the end opening, where it will either be automatically withdrawn from its frictional engagement between the two core members or in some instances the extreme end portion of the tube engaged between the core members may be actually cut or torn from the tube. In either case, however, the free end of the fabric tube will assume its final position shown in Figure 2, wherein it is held under expanding tension between the outer wall of the permanent core member 11 and the adjacent filling material.

Although I have shown and described certain steps and forms of apparatus for the manufacture of filter cartridges, it will be understood that various modifications may be employed therein without departing from the spirit and scope of my invention, as defined in the appended claims.

I claim:

1. In apparatus for packing hollow filter cartridges, a cylindrical packing form open at its upper end and having an axially extending support therein fixed to the bottom thereof, a hollow temporary core member removably mounted on said support and normally extending upwardly beyond the upper end of the latter, and also extending above the rim of said cylindrical form, means for securing the upper end of said core member to the upper end of said support, means for securing one end of a fabric tube to

65 70 75

the upper end of said core member, and other means for securing the opposite end of said fabric tube around the rim of said packing form, while the intermediate portion of said tube is being filled in said form.

2. In apparatus for packing hollow filter cartridges, a cylindrical packing form open at its upper end and having an axially extending support therein fixed to the bottom thereof, a hollow temporary core member removably mounted on said support and normally extending upwardly beyond the upper end of the latter, and also extending above the rim of said cylindrical form, means for securing the upper end of said core member to the upper end of said support, the upper end of said means including a cap for securing one end of a fabric tube to the upper end of said core member, and other means for securing the opposite end of said fabric tube around the rim of said packing form, while the intermediate portion of said tube is being filled in said form.

3. The method of packing filtering material in a hollow, cylindrical filter cartridge having a continuous inner and outer fabric cover and a permanent central core member, which consists of providing a cylindrical packing form of substantially the intended diameter and length of the cartridge, said form having a temporary removable core member therein, anchoring a length of fabric tube for forming said cover adjacent one end thereof to the outer end of said temporary core member, inserting a temporary stretching cylinder within said cylindrical form for substantially the full length of the latter to shape said fabric tube to its full outside diameter, anchoring the other end of said tube to the outer rim of said cylindrical form, packing the portion of said fabric tube intermediate its anchored points with filtering material to form the filtering body of the cartridge while supported within said packing form, then unanchoring the fabric tube from said temporary core member, drawing it outwardly over the adjacent end of said cartridge and tucking its free end between said filtering material and the inner face of the opposite end of said fabric tube, then unanchoring said last named tube end from said form and removing said cartridge and tube fabric from said form, lapping said last named tube end over the adjacent end of said cartridge, and replacing said temporary core member by said permanent core member, with the free end of said last named tube end underlapping the adjacent end of said permanent core member and secured thereagainst by compression of the adjacent filtering material of said filtering body.

4. The method of packing filtering material in a hollow, cylindrical filter cartridge having a continuous inner and outer fabric cover and a permanent central core member, which consists of providing a cylindrical packing form of substantially the intended diameter and length of the cartridge, said form having a temporary removable core member therein, anchoring a length of fabric tube for forming said cover adjacent one end thereof to the outer end of said temporary core member, inserting a temporary stretching cylinder within said cylindrical form for substantially the full length of the latter to shape said fabric tube to its full outside diameter, anchoring the other end of said tube to the outer rim of said cylindrical form, packing the portion of said fabric tube intermediate its

anchored points with filtering material to form the filtering body of said cartridge while supported within said packing form; then unanchoring the fabric tube from said core member, drawing it outwardly over the adjacent end of the cartridge and tucking its free end between said filtering material and the inner face of the opposite end of said fabric tube, then unanchoring said last named tube end from said form and removing said cartridge and tube fabric from said form with said removable core member retained in said cartridge, fitting a permanent core member on the end of said temporary core member with said last named tube end frictionally engaged between said core members, and pressing said permanent core member longitudinally into said cartridge to displace said temporary core member and cause said last-named tube end to be lapped over the adjacent end of said

cartridge and become secured under compression between the end of said permanent core member and the proximate inner face of the inner fabric tube portion when said permanent core member is in its assembled position within said cartridge.

HILMER DAHL.
